[57] CLAIM

The ornamental design for a separator element for a trommel cleaner, shown and described.

DESCRIPTION

FIG. 1 is a perspective of a separator element for a trommel cleaner in accord with the present invention;

FIG. 2 is a front view of the separator element for a trommel cleaner shown in FIG. 1;

FIG. 3 is a side elevation view of the separator element for a trommel cleaner shown in FIG. 1;

FIG. 4 is a side elevation view of the separator element for a trommel cleaner shown in FIG. 1 showing the side opposite to that shown in FIG. 3;

FIG. 5 is a top plan view of the separator element for a trommel cleaner shown in FIG. 1; and,

FIG. 6 is a bottom plan view of the separator element for a trommel cleaner shown in FIG. 1.
